By Burton Burton
his Atty's:

UNITED STATES PATENT OFFICE.

JOHN K. OLSEN, OF CHICAGO, ILLINOIS, ASSIGNOR TO STEWART-WARNER SPEEDOMETER CORPORATION, OF CHICAGO, ILLINOIS, A CORPORATION OF VIRGINIA.

ODOMETER.

Application filed March 30, 1922. Serial No. 548,240.

To all whom it may concern:

Be it known that I, JOHN K. OLSEN, a citizen of the United States, having residence in the city of Chicago, in the county 5 of Cook and State of Illinois, have invented certain new and useful Improvements in Odometers, of which the following is a specification, reference being had to the accompanying drawings, forming a part thereof.

10 The purpose of this invention is to provide an improved construction in an odometer of the type having a continuous indication train and a trip train and means for resetting the trip train. It consists in the 15 elements and features of construction shown and described, as indicated in the claims.

In the drawings:—

Figure 1 is a plan view of an instrument embodying this invention with the outer 20 casing or cover removed and certain parts shown in section axial with respect to the main shaft.

Figure 2 is a section at the line, 2—2, on Figure 1.

25 Figure 3 is a detail section in the same plane as the section at the corresponding parts on Figure 1, showing a detail modification.

In the drawings there is shown an odometer 30 having a frame or casing member, A, having end standards, A¹ and A² in which the main dial-carrying shaft, B, is mounted. The journal bearings for this shaft are provided in these end standards respectively 35 by bushings which are screw threaded into the standards. In the left-hand-end standard, A¹, there is a bushing, C¹, which is axially bored from the inner end to receive and journal the left hand end of the shaft, 40 B, and for housing a coil spring, D, for which an axial bore is provided in the left hand end of the shaft, B, said spring reacting for thrusting the said shaft to the right, and yielding to permit it to be thrust into 45 the left for resetting. In the right-hand-end standard, A², the bushing for journaling the shaft is shown at E, the standard being bored and threaded entirely through 50 its thickness so that the bushing can be screwed in from the outer end to any distance. At the outer end portion the bushing is reduced in diameter and threaded for receiving a jam nut, E¹, set against the end of the boss, a² of the standard into which 55 the bushing E, is screwed. On the shaft,

B, there are mounted dial wheels of a continuous-indication train, F¹, F², F³, F⁴ and F⁵; and toward the other end the dials of the trip train, G, G¹, and G². The train is actuated by gear means engaging a gear, H, 60 which is mounted on the shaft, B, intermediate the trip train and the continuous indicating train, the driving gear means being indicated by the spiral gear pinion, H¹, shown in dotted line, carried on the shaft 65 whose end for engagement with a flexible drive shaft which operates it (not shown) is shown at h¹, said shaft being journaled in the bearing, A³, formed integrally with the frame, A. Driving movement is communicated to the train from the gear, H, through the medium of the mutilated or single-toothed gear wheels, K¹, K² and K³, and the speed-reducing or carrying pinions, L¹, L² and L³, on the counter-shaft, 1, on which 70 also are the carrying pinions for carrying 75 decadimally from dial wheel to dial wheel, of the continuous indicating train, as well as the trip train. These speed reducing or carrying means are familiar and need not be further described, and are here indicated only conventionally or in outline. It will be understood that the first mutilated or single toothed gear, K¹, is rigid with the 80 gear, H, and that the remainder of the 85 wheels are loose upon the shaft, B. The third speed reducing gear, K³, has a spline-and-groove engagement with the shaft by means of a pin or spline, f, engaging a longitudinal groove, b, in the shaft at the normal position of the parts; and the shaft, B, has a circumferential groove, b¹, positioned for engagement with the spline pin, f, when the shaft is thrust inward longitudinally for resetting,—compressing the spring, 90 D,—so that the shaft may be rotated for resetting without operating the continuous-indication train. The construction in these respects is substantially identical with that 95 of my application No. 533,175 filed February 1, 1922, and now pending. J is a spacer on the shaft, B, between the third dial wheel, G², of the trip train and gear, H, having no other purpose except to facilitate the process of manufacture and assembling by constituting a member which can be promptly dressed as to its thickness to accurately occupy with the dial wheels the space on the shaft between the end standards so that the 100 spline pin, f, shall register correctly with the 105 110

groove, b^1 , at the inthrust or resetting position of the shaft, thus providing for unavoidable variations which may amount to a few thousandths of an inch in the dimensions of the frame or its wheel contents.

As a further means of insuring the correct registration of the spline pin, f , in the groove, b , and in the groove, b^1 , at the respective positions of the shaft, and in view 10 of the convenience of assembling, the construction of the journal bearing bushing, E , for the right hand end of the shaft, is as shown and partly already described,—that is, such that the bushing may be screwed 15 in from the right hand end of the frame to any proper distance along the bushing; and there is provided in the bushing a chamber, as seen at e^2 , about the portion of the shaft in which there are formed two grooves, 20 b^3 and b^4 , for engagement by a spring key, M , seen most clearly in Figure 2, this key being positioned longitudinally of the shaft axis by being housed closely in the bushing, so that as the shaft is thrust or pulled 25 endwise, the spring key snaps over from one groove to the other, positioning the shaft either for normal operation or for resetting. In the form shown in Figures 1 and 2, the bushing is constructed for providing this 30 housing for the spring key, M , by being made in two parts or members, to the outer or principal member of which the reference letter, E , is applied, the inner member being shown at E^* . Both members are 35 threaded for screwing into the threaded aperture in the frame, and they are provided at their proximate ends or faces with means for interlocking, consisting of two lugs, e^6 , e^6 , projecting from the main bushing member, E , and e^7 , e^7 , projecting from 40 the auxiliary bushing member, E^* , the lugs of one pair standing in circumferential order between the two lugs of the other pair, so that the rotation of the main bushing 45 member, E , in either direction will rotate the auxiliary member, E^* , in the same direction and substantially without lost motion. These lugs by their length serve as spacers for spacing the two bushing members apart to form and definitely dimension 50 the housing for the spring key.

In the form shown in Figure 3 the same function of the bushing member as a means of carrying the spring key, M , is effected 55 by providing in the chamber, e^2 , a filler or collar, E^5 , whose axial length adapts it to cover and mask the right hand end groove, e^5 , when the shaft is at its normal or outward position; and a thin washer, E^8 , is engaged with the bushing near its inner end where the bushing is provided with a shoulder, e^8 , for lodgment of the washer which is secured by "staking" over the end of the bushing onto the margin of the washer, as 60 clearly seen in Figure 3.

In either of the constructions shown, it will be understood that the bushing, which is slotted for engagement with a proper operating tool, as seen at e^9 , should be screwed into the standard of the frame, as far as 70 may be necessary to accurately adjust the shaft for registering of the spline, f , with the grooves, b and b^1 , at the proper time, and will then be secured in adjusted position by the jam nut, E^1 . 75

I claim:—

1. In an odometer having a continuous indication train and a trip train, and having a shaft for the trip train which is arranged to be thrust longitudinally a substantial distance for disengagement from the continuous train for resetting the trip train, in combination with a frame or casing, a bushing mounted and longitudinally adjustable in said frame, a journal bearing distinct from the bushing supported and longitudinally stopped therein, the trip train shaft journaled in said bearing and means for yieldingly holding it at a plurality of positions longitudinally therein; whereby said shaft is carried longitudinally with the longitudinal adjustment of the bushing, separately and independently of its adjustment from one to another of its several positions in the journal bearing and means for securing the bushing at adjusted position in the frame. 95

2. In an odometer having a continuous indication train and a trip train, and having a shaft for the trip train which is arranged to be thrust longitudinally a substantial distance for disengagement from the continuous train for resetting the trip train, in combination with a frame or casing, a journal bearing, means by which it is mounted and longitudinally adjustable in the frame 100 and means for securing it at adjusted position; the trip train shaft journaled in said bearing, and means for yieldingly holding it at a plurality of positions longitudinally therein; whereby said shaft is carried longitudinally with the longitudinal adjustment of the bearing, separately and independently of its adjustment from one to another of its several positions in said bearing. 105

3. In the construction defined in claim 1, 115 foregoing, means by which the bushing positions the shaft, comprising a spring key carried by the bushing, and a groove in the shaft engaged by the spring key.

4. In the construction defined in claim 1, 120 foregoing, the means by which the bushing positions the shaft comprising a spring key carried by the bushing, the shaft having two grooves for alternative engagement with said spring key, the one at normal position and the other at resetting position, the bushing being constructed for housing and positioning the spring key so that said key is carried with the bushing in the adjustment 125 of the latter. 130

5. In the construction defined in claim 1, bushing comprising two members which are 15
foregoing, the means by which the bushing interlocked for rotation in adjusting the
positions the shaft, comprising a spring key bushing, and spaced at their interlocked
carried by the bushing and a groove in the ends for housing and positioning the spring
5 shaft engaged by the spring key, the bushing key, said interlocking housing members being
comprising two members which are interlocked for rotation in adjusting the bushing
10 and spaced at their interlocking ends 20 from the proximate faces of said bushing
members, the length of said projections serving to space said member apart for housing
the spring key without binding the latter.
- In testimony whereof, I have hereunto set 25
my hand at Chicago, Illinois, this 27 day of
March, 1922.
- JOHN K. OLSEN.
